COMBINED LIGHTING FIXTURE AND RECORD STORAGE UNIT

James R. F. Miller, 3201 Bayview,
Manhattan Beach, Calif.

Filed Oct. 2, 1961, Ser. No. 66,950

Term of patent 14 years

Cl. D33—3)

FIG. 1 is a front elevational view of a combined lighting fixture and record storage unit showing my design, the back thereof being like the front except for the lamp which extends forwardly,

FIG. 2 is a side elevational view thereof, and

FIG. 3 is a view similar to FIG. 1, showing one of the record receptacles in an open position.

I claim:

The ornamental design for a combined lighting fixture and record storage unit, as shown and described.
